UNITED STATES PATENT OFFICE.

JOHN O. GOODWIN, OF HARRISBURG, PENNSYLVANIA.

LIQUID-FUEL BURNER.

1,302,360.

Specification of Letters Patent. Patented Apr. 29, 1919.

Application filed February 11, 1918. Serial No. 216,509.

To all whom it may concern:

Be it known that I, JOHN O. GOODWIN, a citizen of the United States, residing at Harrisburg, in the county of Dauphin and State of Pennsylvania, have invented certain new and useful Improvements in Liquid-Fuel Burners, of which the following is a full, clear, and exact description.

The invention, which constitutes the subject matter of this application, relates to improvements in liquid fuel burners. Specifically the invention has to do not only with certain structural features pertaining to simplicity but with a device which may be operated by steam and superheated air and by steam alone. Any kind of liquid fuel may be employed but the burner is particularly adapted to burn coal tar or coke oven tar which is very heavy and much difficulty encountered to obtain the proper atomization of the tough particles therein.

Referring to the drawings:

Figure 1 illustrates a longitudinal section of my improved device on line $x-x$ of Fig. 3.

Fig. 2 is a cross section of the device taken on line $y-y$ of Fig. 1.

Fig. 3 is an end view of the device.

Fig. 4 illustrates a modified form of the nozzle taken on the line 4-4 of Fig. 6.

Fig. 5 is a section taken on the line 5-5 of Fig. 6.

Fig. 6 is a front view showing the discharge end of the nozzle.

Fig. 7 is a cross section on line 7-7 of Fig. 5.

In detail the reference numeral 10 designates the body of the burner, preferably cast, to which the various parts are connected. This body is provided with a chamber 11 to which the tar or other oil is admitted through pipe 12 the latter being provided with a valve 13 to regulate the supply of fuel to the chamber 11. To the projection 14 is connected a steam pipe 15 provided with a valve 16 to regulate the flow of steam through the nozzle 17, the latter being suitably secured to the projection 14. Located within and secured to the body 10 is a second nozzle 18 having flaring ends 19 and 20 and the neck or restricted portion 21. As will be seen from Fig. 1, the interior of nozzle 17 flares outwardly relative to the direction of flow of the steam, the inner end of which is located adjacent to the end of the flare 19 of nozzle 18. The inlet to the in-

wardly flaring portion 19 is slightly larger than the discharge end of nozzle 17. This enables the steam ejected from the nozzle 17 to draw into the nozzle 18 a thin sheet of tar or oil from the chamber 11, and to break up the tough texture of the tar. This steam coming into contact, as it does, with the tar becomes somewhat condensed. The commingled steam and tar now pass through the restricted portion 21 of the nozzle 18 and not only become equalized in temperature and thoroughly mixed but result in a heavy vapor. This vapor passes out of the flared end 20 of the nozzle 18 into the member or expansion chamber 22 located in the heating compartment 23, the latter being defined by the body 10 and the casing 24 screw-threaded thereto. The member 22 is preferably screw-threaded to the burner body and seats on the shoulder 25 of the nozzle 18 to hold the latter in place. This facilitates the removal of the nozzle 18 when that is desired.

Superheated steam or air from any suitable source, is admitted to the compartment 23 through pipe 26, the latter being provided with a valve 27 to regulate the flow. The walls of the member 22 are preferably quite thin to enable a rapid heat transfer from the heating chamber to the heavy vapor inside of said member. The heating of the vapor in this manner causes the tar to become thoroughly atomized. The member 22 preferably flares outwardly at its outer end and is provided with a spider 28 to which is screw-threaded a conical member 29. This conical member is provided with a laterally projecting lip 30 somewhat larger than the inner walls of the outlet end of the member 22 thus tending to deflect the vapor at right angles to the axis of the member 22. The outer end of the casing 24 and the outer end of the member 22 terminate in substantially the same plane and define an outlet 31 for the fluid passing through the heating compartment 23. The superheated steam or air flowing between the walls of the heating compartment and the outer walls of the member 22 raises the temperature of the vapor to any desired degree, and in its discharge the heating fluid strikes the superheated vapor at right angles carrying it backward into the combustion chamber of the furnace (not shown), resulting in a perfect combustion of the fluid and vapor. Combustion may take place immediately in front of the burner or it may be forced back

into the combustion chamber by increasing the rate of flow of the heating fluid through pipe 26 and heating chamber 23.

The area of the outlet 32 being approximately equal to that of the restricted portion 21 of the nozzle 18, the flow of the vapor through the member 22 is sufficiently retarded to enable it to be heated to the temperature at which it is transferred into a gaseous vapor before being discharged into the combustion chamber. The walls of the various parts of the burner are constructed with a view of obtaining a minimum resistance to the flow of fluid therethrough, while at the same time providing a thorough mixing of the vapor and steam.

The conical member 29 is adjustably secured to the member 22 and for the purposes of assembling, removal and adjustment it is provided with recesses 33 adapted to receive a spanner, and for the purpose of maintaining said conical member in any adjusted position I employ a set screw 34 which cooperates with the spider 28 to lock the conical member against rotation.

In Figs. 4 to 7 inclusive is illustrated a modified form in which the discharge nozzle 35 is flattened, made in one piece with the superheating chamber 36, and preferably screw-threaded to the body 10 of the burner. Either form of nozzle may be employed with the body 10.

From the foregoing it will be readily apparent that I have devised a burner adapted to produce within itself a perfect combustible mixture, and provided with suitable means for adjusting the various parts to meet the particular exigencies or conditions ordinarily met with in using a device of this character. It is to be understood, however, that I do not limit myself to the exact constructions illustrated and described as various changes may be made in points of detail and other embodiments resorted to without deviating from the true spirit and scope of my invention.

I claim:—

1. A burner of the class described, comprising a body having a liquid fuel receiv-

ing chamber and a heating chamber, a steam nozzle, the discharge end of which is located in said liquid fuel receiving chamber, a receiving member for the steam and fuel, the inlet to which is adjacent to and of greater diameter than the discharge end of said nozzle and the central portion of which is reduced to compress the steam and fuel and equalize the temperature thereof, in combination with a member or chamber, located within said heating compartment, adapted to vaporize the fuel from the receiving chamber, and means for effecting a mixture of superheated steam or air from the heating compartment and the vaporized material from the expansion chamber.

2. A burner of the class described, comprising a body having a liquid fuel receiving chamber, a steam nozzle, the discharge end of which is located in said chamber, a vaporizing tube into which steam from said nozzle and fuel from said chamber is injected, in combination with a superheater within the burner itself for vaporizing the fuel.

3. A burner of the class described, comprising a body having a liquid fuel receiving chamber, a steam nozzle the discharge end of which is located in said chamber, a vaporizing tube into which steam from said nozzle and fuel from said chamber is injected provided with means for retarding the flow of vapor therethrough, in combination with a superheater within the burner itself for atomizing the vapor.

4. A burner of the class described, comprising a body having a liquid fuel receiving chamber, a steam nozzle the discharge end of which is located in said chamber, a vaporizing tube into which steam from said nozzle and fuel from said chamber is injected, and an adjustable member in the end of said tube for retarding the flow of vapor therethrough, in combination with a superheater within the burner itself for atomizing the vapor.

In testimony whereof I hereunto affix my signature.

JOHN C. GOODWIN.
